UNITED STATES PATENT OFFICE.

WILLIAM G. STEWART, OF CLEVELAND, OHIO.

COMPRESSION FAUCET.

Application filed October 26, 1926. Serial No. 144,368.

This invention relates to faucets and consists in certain improvements in the construction and arrangement of parts as will be hereinafter more fully described and 5 pointed out in the appended claims.

The main object of the invention is to provide a faucet of the character described in which the valve, valve seat and valve actuating mechanism are readily removable 10 through the top of the casing without disconnecting the casing from the source of water supply.

A further object of the invention is to provide a faucet of the character described 15 in which the valve seat may be reground or dressed without removing the same from the casing.

Another object of the invention is to provide a faucet of the character described in 20 which the valve is carried by a plug in the top of the casing which is readily removable for repair or replacement.

A further object of the invention is to provide a faucet of the character described 25 in which may be readily assembled and disassembled and which is well adapted for quantity production at comparatively low cost.

Further and more limited objects of the 30 invention will appear as the description proceeds and by reference to the accompanying drawing in which Fig. 1 is a vertical sectional view thru the device. Fig. 2 is a view similar to Fig. 1. Fig. 3 is a section 35 on the line 3—3 of Fig. 2.

According to the preferred embodiment 40 of my invention disclosed in the accompanying drawing the numeral 1 designates the casing or faucet base provided with a depending portion which is exteriorly threaded at its lower end, as shown at 2, for attachment to a source of water supply. The base 1 is provided with an overhanging annular flange 3 and a spout 4 preferably cast 45 integral therewith. The casing is also provided with a bore 5 communicating at its upper end with the spout 4 and threadedly secured in the upper end of the bore 5 is a hollow tubular member 6, the purpose of 50 which will hereinafter appear. The casing 1 is open at its upper end and is both interiorly and exteriorly threaded. Threadedly received in the upper end of the casing 55 is a sleeve 7 which is open at its upper end and threadedly receives therein a plug 8 to

the lower side of which is secured a valve 9 which is readily removable from the plug 8. Secured over the upper end of the sleeve 7 in any suitable manner so as to be readily removable therefrom and to turn therewith 60 is a valve actuating member 10. The upper end of the casing is closed by means of a cap 11 and suitable packing 12. The sleeve 7 extends through the cap 11 and has a sliding fit therein. The tubular member 6 extends through the casing a sufficient distance so that when the plug 8 is removed and the sleeve 7 is screwed down to the position shown in dotted lines in Fig. 1, the upper end of the tubular member 6, which 65 constitutes the valve seat, will be exposed and project through the upper end of the sleeve and be readily accessible for re-grinding or repair.

In assembling the faucet the tubular 70 member 6 is first inserted and screwed into place. The sleeve 7 is then screwed into the upper end of the casing and the plug 8 with the valve 9 secured thereto is then screwed into the upper end of the sleeve 7. The valve 75 actuating member 10 is then placed over the upper end of the sleeve and secured against rotation with respect to the sleeve by means of a set screw or if desired the upper end of the sleeve may be provided 80 with relatively small longitudinally extending ribs and the valve handle pressed thereon in such a manner that the handle and sleeve turn together. When it is desired to dress the valve seat, the plug 8 may be removed and the sleeve 7 screwed down until the upper end of the tubular member 6 projects above the upper end of the sleeve. The upper end of the tubular member 6, which 85 constitutes the valve seat, may then be filed down or ground in any suitable manner. In this connection it may be pointed out that any sediment or other foreign matter which may be contained in the water flowing through the casing flows over the 90 top of the tubular member 6 and is carried downwardly and out through the spout 4 and that due to this arrangement it is not possible for any foreign matter to lodge and be retained on the valve seat.

In Fig. 2 I have disclosed a modified form 95 of my invention in which the tubular member 6' is exteriorly threaded as shown at 7' and the sleeve 8' is provided at its lower end with a spider 9' having a threaded opening 100

- 10' therein. In this form of the invention the sleeve has no threaded engagement with the casing but is merely slidable therein. In other respects the two forms of the invention 5 may be identical and operate in the same manner.
- It will now be clear that I have provided a faucet and valve mechanism therefor which will accomplish the objects of the 10 invention as hereinbefore stated.
- Having thus described my invention, what I claim is:—
1. A faucet of the character described comprising a casing having one end open and its opposite end adapted to be connected with a source of water supply, a tubular member secured within said casing and extending upwardly through the upper end thereof, a sleeve slidably secured within 15 said casing, a valve carried by said sleeve and movable to a position to close the upper end of said tubular member, said sleeve being movable to a position to expose the upper end of said tubular member above the top of said sleeve without removing said sleeve from said casing, and an outlet leading 20 from said casing.
  2. In a faucet of the class described, a casing having its upper end open and its lower end adapted for attachment to a source of water supply, a tubular member secured within said casing and having its upper end shaped to provide a valve seat, a sleeve slidably secured within said casing and surrounding 25 said tubular member, said sleeve projecting above the top of said casing and having a plug removably secured in the upper end thereof, a valve carried by said plug adapted to close the upper end of said tubular member, means for moving said sleeve to a position to render the upper end of said tubular member accessible without removing said sleeve from said casing, and an outlet leading 30 from said casing.
  3. In a faucet of the class described, a casing having a bore extending longitudinally thereof, a tubular member secured within the upper part of said bore and having its upper end disposed above the top of said casing, a sleeve slidably secured in said casing and surrounding said bore, a removable plug closing the upper end of said sleeve, a valve carried by said plug and adapted to close the upper end of said tubular member, said sleeve being movable to 35 a position to expose the upper end of said tubular member above the top of said sleeve.
  4. In a faucet of the class described, a casing having a bore extending longitudinally therethrough, a tubular member secured within said bore, a sleeve secured within said casing and surrounding said tubular member, a valve carried by said sleeve for closing the upper end of said tubular member, and means for moving said 40 sleeve to a position to render the upper end of said tubular member accessible for repair.
  5. A faucet of the class described comprising a casing having an inlet passageway leading thereinto and an outlet leading therefrom, a tubular member secured in said inlet passageway and extending through said casing, the upper end of said tubular member being shaped to provide a valve seat, a member secured within said casing and movable with respect thereto, a valve carried by 45 said member and adapted to engage said valve seat to shut off the flow through said faucet, and means for moving said member to a position to render said valve seat accessible for repair without removing said tubular member from said casing.
  6. A faucet of the class described comprising a casing having an inlet passageway leading thereinto and an outlet leading therefrom, a tubular member secured in said inlet passageway and having its upper end shaped to provide a valve seat, a sleeve secured within said casing and movable with respect thereto and surrounding the upper end of said tubular member, a valve member detachably connected with said sleeve and adapted to engage said valve seat to cut off the flow through said faucet, means for moving said sleeve with respect to said tubular member to render said valve seat accessible for repair without removing said tubular member from said casing.
  7. A faucet of the class described comprising a casing having an inlet passageway leading thereinto and an outlet leading therefrom, a tubular member secured within said inlet passageway and extending upwardly through said casing, a sleeve secured within said casing and surrounding the upper end of said tubular member, a plug detachably secured to said sleeve and closing the upper end thereof, a valve carried by said plug, a handle secured on said sleeve so as to turn therewith, a cap positioned on said sleeve and threadedly secured to said casing, said sleeve being movable to a position to expose the upper end of said tubular member through the top thereof when said plug is removed.
  8. A faucet of the class described comprising a casing having an inlet passageway leading thereinto and an outlet leading therefrom, a tubular member arranged within said inlet passageway and having its upper end adapted to provide a valve seat, a sleeve secured within said casing and surrounding the upper end of said tubular member but spaced therefrom and having a valve member detachably secured thereto and adapted to engage said valve seat, means for moving said sleeve to open and close said valve, said sleeve being movable to a position to expose said valve seat through the

top of said casing, when said valve member is removed from said sleeve.

9. A faucet of the character described provided with an inlet passageway leading 5 thereinto and an outlet leading therefrom, a tubular member arranged within said inlet passageway and having its upper end adapted to provide a valve seat, a sleeve 10 threadedly secured within said casing and surrounding the upper end of said tubular member but spaced therefrom, a plug detachably connected with said sleeve, a valve carried by said plug and adapted to engage said valve seat, and means for actuating said sleeve to 15 open and close said valve, said sleeve being movable to a position to render said valve seat accessible for repair when said plug is removed.

10. A faucet of the class described comprising a casing having an inlet passageway

and an outlet spout and having means for rigidly connecting the same with a supply pipe, a tubular member disposed within said inlet passageway and extending upwardly through the top of said casing, a sleeve 25 threadedly secured within said casing and surrounding the upper end of said tubular member but spaced therefrom so as to provide an annular space therebetween, a valve member detachably secured to said sleeve 30 and so disposed as to close the upper end of said tubular member, a handle for operating said sleeve to open and close said valve, said sleeve being movable to a position to expose the upper end of said tubular member through the top thereof when said valve member is removed.

In testimony whereof, I hereunto affix my signature.

WILLIAM G. STEWART.
